(57) **CLAIM**

The ornamental design for an electrical evaporator for volatile materials, as shown.

DESCRIPTION

FIG. 1 is a front and right side perspective view of an electrical device showing my new design;

FIG. 2 is a front view thereof;

FIG. 3 is a rear view thereof;

FIG. 4 is a top plan view thereof;

FIG. 5 is a bottom plan view thereof;

FIG. 6 is an enlarged right side view thereof; and,

FIG. 7 is an enlarged left side view thereof.
